UNITED STATES PATENT OFFICE.

CHARLES J. HODGE, OF HOOGLTON, MICHIGAN.

DESIGN FOR A FRAME FOR SUPPORTING ORE OR MINERAL WASHING JIG-SCREENS.

SPECIFICATION forming part of Design No. 29,930, dated January 3, 1899.

Application filed December 12, 1898. Serial No. 699,070. Term of patent 7 years.

To all whom it may concern:

Be it known that I, CHARLES J. HODGE, a citizen of the United States, residing at Houghton, in the county of Houghton and State of Michigan, have invented and produced a certain new and original Design or Useful Shape for a Frame for Supporting Ore or Mineral Washing Jig-Screens, of which the following, in connection with the accompanying drawings, is a full, clear, and exact specification.

In the said drawings, Figure 1 is a plan view of a frame of the character described embodying my design; and Fig. 2 is a side elevation thereof, partly in section, on the irregular line 2 2, Fig. 1.

The leading features of my design consist of the marginal frame portion A and the plurality of concentric curved or circular portions B, connected by transverse bars C.

The frame portion A is rectangular and oblong, and it is provided throughout in its upper surface at short intervals with circular sockets a, which are surrounded by circular bosses a'. The outer circular bars B, the ends of the next bars B, and the outer cross-bars C merge into the frame A, and the frame A on its inner side at all points, excepting where said bars merge therewith and where the bosses a' are located, are beveled or rounded, 30 as shown at a''.

The bars B are concentric circles and arcs which are connected together by the cross-bars C, which radiate from the center of the innermost circle, and the cross-bars C are so arranged that no two contiguous ones will be 35 in direct line.

The bars B C are very narrow as compared with the frame A and also with their depth, and they are coterminous in depth with the frame A, so that their upper and lower edges 40 will be flush with or in the same plane as the upper and lower edges, respectively, of the frame A. The bars B C are tapered from their lower to their upper edges, which latter edges are rounded.

Formed at one end of the frame and at the point of junction between one of the circular webs or bars B and one of the cross-bars C is a circular perforated boss D.

Having thus described my invention, what 50 I claim as new therein, and desire to secure by Letters Patent, is—

The design for a frame for supporting ore or mineral washing jig-screens substantially as herein shown and described.

CHAS. J. HODGE.
